UNITED STATES PATENT OFFICE.

EDWARD KAYE, OF PHILLIPSBURG, ASSIGNOR TO THE PHOENIX GLASS COMPANY, OF PITTSBURG, PENNSYLVANIA.

DESIGN FOR A LAMP-CHIMNEY.

SPECIFICATION forming part of Design No. 15,470, dated October 21, 1884.

Application filed July 7, 1884. Term of patent 3½ years.

To all whom it may concern:

Be it known that I, EDWARD KAYE, a citizen of the United States, residing at Phillipsburg, in the county of Beaver and State of Pennsylvania, have invented and produced a new and original Design for Lamp-Chimneys, of which the following is a specification, reference being had to the accompanying drawings, forming a part thereof.

10 My design has relation to lamp-chimneys; and it consists in a chimney the upper edge of which presents alternately deep and shallow radial recesses at equal distances apart, and intervening projections having rounded edges, each rounded edge terminating in a deep and shallow recess, respectively.

15 In the drawings, Figure 1 is a perspective view of a lamp-chimney embodying my design. Fig. 2 is an enlarged perspective view of the top of the chimney embracing the design. Fig. 3 is a top view of the same.

A designates the body of the chimney.

B B B represent radial indentations, depressions, or recesses, and C C C similar radial indentations, depressions, or recesses between 25 the recesses B B B, but of less depth.

D D D are the projections or "beads" occupying the spaces between the indentations or recesses, and terminating each in a deep and shallow recess, respectively. 30

What I claim is—

The design for a lamp-chimney, consisting of the alternately deep and shallow indentations or recesses and the intervening curved beads or projections of equal height, as shown. 35

In testimony that I claim the foregoing as my own I have hereunto set my hand and seal, this 30th day of June, A. D. 1884, in presence of two witnesses.

EDWARD KAYE. [L. S.]
